ATTORNEY.

UNITED STATES PATENT OFFICE.

CHARLES C. BOGARDUS, OF LOS ANGELES, CALIFORNIA.

UPPER-CYLINDER OILER.

Application filed November 16, 1926. Serial No. 148,641.

The invention forming the subject matter of this application is a metering device designed to provide lubrication for the upper parts of the cylinders of internal combustion engines and for the valve stems and other moving parts of such engines in communication with the combustion chambers thereof. It is particularly designed to feed a lubricant, invented by the applicant and well known in the art, soluble in petroleum distillates, such as kerosene, gasoline, etc., and having a castor oil base, into the liquid fuel as it is fed from a storage tank to the combustion chambers of an internal combustion engine, and in quantities which may be varied to secure any desired proportions between the fuel transferred and the lubricant introduced therewith. This lubricant requires no mechanical mixing with the fuel and is liberated from its solvent in the combustion chambers of the engine when the lubricated fuel is burned therein, thereby serving to lubricate the pistons, valves and valve stems, etc., not ordinarily accessible to the lubricating system of the engine. When the liquid fuel—gasoline for example—with this lubricant dissolved therein, is burned in the combustion chambers of the engine, the solvent gasoline burns before the much slower burning castor oil solute and leaves a film of oil to lubricate all parts of the engine in communication with said chambers.

While the main object of the invention is to feed a lubricant soluble in gasoline, or a similar liquid fuel, to the fuel during its passage from a storage tank to the combustion chambers of an internal combustion engine, it must be understood that the invention is not limited to such use, as it may be used to introduce any other kind of fuel treating liquid into the fuel during its passage from a main storage tank to the usual gravity feed auxiliary tank or to any other feed line leading to the carburetor of the engine.

Other objects of the invention will appear as the detailed description of my invention proceeds.

50 In the drawing:—

Figure 1 is a side elevation of my invention as applied in a general way to the fuel transferring apparatus of an internal combustion engine in common use;

Figure 2 is a central vertical section 55 through my liquid metering device;

Figure 3 is a fragmentary detail; and

Figure 4 is a fragmentary elevation of my invention as embodied in a fuel feed system 60 of the pressure feed type.

As shown in the drawing, the supply tank 1 is connected by the feed line 2 to the vacuum tank 3 which is suitably supported on the engine adjacent the dashboard 4. A pipe 5 connects the tank 3 to the intake 65 manifold 6 of the engine 7, and a second pipe 8 connects the bottom of the tank 3 to the carburetor 9. Everything so far described is old and well known in the art 70 and forms no part of my invention, except as it may enter into combination with my metering device.

The metering device proper comprises a container 10 adapted to be secured by any suitable means such as the straps 11 to the 75 tank 3, or wherever found most convenient. The container 10, which may be in the form of a bottle made of glass or other suitable material, has its neck 12 provided with a flange 13 underneath which a band 14 is 80 suitably clamped and arranged to form a support for the pivots 15 projecting diametrically opposite therefrom. A yoke 16 has its ends pivoted on the pivots 15 and is provided centrally with a screwthreaded aperture 17 in which the set screw 18 threaded. A lock nut 19 on the screw 18 locks said screw against accidental displacement on the yoke 16.

The lower part of the cap C is recessed to 90 provide a vertical flange 19 fitting snugly into the neck 12 and also to provide a lateral flange 21 adapted to be pressed down tightly against the gasket 22 interposed between the flange 21 and the top of the neck 95 12. The upper part of the cap C is solid and is provided with a conical depression 23 adapted to receive the conical end of the set screw 18. It will be obvious from the drawing that the yoke 16 and the setscrew 18 100 serve to clamp the cap C securely to the container 10, and that they can be readily out of clamping engagement with said cap whenever it becomes necessary or desirable to remove said cap.

A small portion of the lubricant L in the container 10 is sucked into the tank 3 every time said tank is placed under engine suc-

tion. The amount sucked into said tank at one time is controlled by the adjustment of the needle valve 23 relative to its valve seat 24 formed in the valve fitting 25 which is connected by the pipe 26 to the T-joint 27 at the top of the tank 3. The T-joint 27 is screwthreaded at one end into the pipe 28 which is, in turn, screwed into the usual inlet plug hole at the top of the tank, and the plug 29 closed the other end of the T-joint 27. This method of joining the top of the cap C to the vacuum tank 3 permits the tank to be filled at any time by simply removing the plug 29.

15 The valve 23 rotates and moves axially in a bore 30 extending laterally more than half way through the cap C and having its end screwthreaded to receive and support the valve fitting 25. A second bore 31, at right angles to the bore 30, receives and supports the upper end of the tube 32 which extends downwardly to the bottom of the container 10. The tube 32 has its lower end provided with a ball valve fitting 33 of any convenient type, and a ball 34 in said fitting if normally held either by gravity or by a spring 35 to close the aperture 36 in the end of the fitting 33. A vent 37 at the top of the cap C places the said cap and container 10 under atmospheric pressure.

20 The head 38 of the valve 23 is provided with an indicator line 39 adapted to be read against the indications 40 formed on the cap C.

25 It will be obvious that every time the vacuum tank is placed under engine suction, the container is also placed under suction and a small quantity of lubricant L is sucked from the container into the tank to be dissolved in the fuel in said tank. The quantity of fuel drawn into the tank 3 at each suction operation can be readily determined, and the quantity of lubricant introduced into this quantity of fuel can be readily controlled by adjustment of the valve 23 to secure the desired proportions between the fuel and lubricant.

30 While I have shown the oiler as applied to a vacuum tank connected to the intake manifold of an internal combustion engine, it must not be considered as limited in its

application. It may be connected to any feed line, and its rate of lubricant feed proportioned to the rate of flow of fuel through the line. For example, in Figure 55 4, there is shown a container 41 for lubricant L adapted to be secured wherever found convenient relative to the carburetor 42 of the pressure feed type. The container 41 is provided with a filler plug 42 and is not vented to the atmosphere. A pipe 43 connected to the source of pressure (not shown) of the fuel feed system, places the lubricant L under the same pressure as the fuel feed to the carburetor through the feed line 44, and a needle valve 45 proportions the rate at which the lubricant is drawn from the container 41 by the flow of fuel through the pipe 44 to the rate of flow of fuel through said pipe 44. The container 41 may be provided with a sight glass 46 to show the depth of lubricant in the container. The container 41 must have the same pressure as the feed system in order to prevent fuel being forced into the lubricant container, and to ensure lubricating liquid being drawn by aspiration of the fuel in pipe 44.

75 I claim:—

1. In combination with an internal combustion engine and a source of fuel supply 80 therefor, of means including a vacuum tank operatively connected to said engine for transferring fuel from said source of supply to said engine, and means operated by the vacuum intermittently induced in said tank for introducing a liquid into the fuel in said tank.

2. The combination with an internal combustion engine having a carburetor and a source of fuel supply therefor, of a conduit 90 connecting the float chamber of said carburetor to said source of supply, a liquid container connected to said conduit and adapted to feed liquid to the fuel passing through said conduit to said float chamber, and a 95 manually adjustable valve for controlling the rate of feed of liquid from said container to said conduit.

70 In testimony whereof I have signed my name to this specification.

CHARLES C. BOGARDUS.
